UNITED STATES PATENT OFFICE.

MARGARET B. CRANK, OF LOS ANGELES, CALIFORNIA.

HOUSE-GARMENT.

1,379,902.

Specification of Letters Patent. Patented May 31, 1921.

Application filed March 31, 1920. Serial No. 370,090.

To all whom it may concern:

Be it known that I, MARGARET B. CRANK, a citizen of the United States, residing at Los Angeles, in the county of Los Angeles and State of California, have invented new and useful Improvements in a House-Garment, of which the following is a specification.

This invention relates to an improved 10 one-piece garment adapted to be slipped over and to protect the clothing.

It is an object of this invention to provide a garment simple to make, inexpensive, ornamental in appearance, having no but- 15 tons, hooks, buckles, or other fasteners. It is another object of this invention to provide a garment easily laundried.

These objects will be more fully understood, as will also other objects and cor- 20 responding accomplishments of my invention from the following detailed description of a preferred embodiment thereof. For the purpose of this description reference is had to the accompanying drawing, in which:

25 Figure 1 is a front view of the garment as worn;

Fig. 2 is a rear view thereof; and

Fig. 3 is a view of the garment spread out, before being sewed at the sides.

30 The body of the garment indicated generally by A is made of a single piece of material. A combined waist band and bib is attached to the body adjacent the neck and is indicated generally by B. Pockets 35 C are also provided. The shapes of the waist band and pockets are such that they may be cut from the same material as the body without any waste of material.

Referring particularly to Fig. 3, the body 40 A comprises lobes 4 and 5 extending from a shoulder portion 6. The lobes comprise the front and back of the garment and are substantially the same in shape and size. However, the front is somewhat wider, in 45 order to make the garment conform more nearly to the shape of the body of the wearer. Extending laterally from the shoulder portion are arms 7. At the center a neck opening 8 is cut. The body shown 50 herein is without any waist line.

Secured to the body at the front part of the neck opening is the combined waist band and bib. The only point at which it is secured is at a seam indicated by 9. The 55 bib portion is indicated by 10, depending from the neck flaring outwardly and terminating at the sides in bands 11 adapted to be extended about the body and to be tied or otherwise fastened. Sewed to the front of the garment are the pockets C.

The garment is completed by folding it along the median line 12—12 and sewing the side edges together.

The garment when complete must be slipped on over the head of the wearer, and 65 removed in this fashion. After it has been placed on the body the waist bands are crossed in the rear and tied or otherwise suitably fastened. The bib and waist band draw in the garment at the waist line so 70 that the bodice portion is shaped to the curves of the body and provides the garment with a waist line enhancing its appearance. The bib covers the front of the garment and presents a smooth vest effect. 75

It is obvious that by reason of the simplicity of structure, the absence of buttons, hooks, buckles, or fasteners, it may easily be laundried. The single piece bib and 80 waist band is also free and flat so that it does not interfere with the ironing of the garment.

It is obvious that by reason of the simplicity of structure, the absence of buttons, hooks, buckles, or fasteners, it may easily be laundried. The single piece bib and 80 waist band is also free and flat so that it does not interfere with the ironing of the garment.

What I claim is:

1. An outer garment comprising a single piece of material formed of a shoulder portion and front and back lobes folded and fastened at the edges to form a body with a neck portion, and a bib and waist band secured to the body at the neck and freely extending therefrom so that the waist band portion may be drawn about the waist of said body to provide a smooth vest and a girdle.

85

2. An outer garment comprising a single piece of material formed of a shoulder portion and front and back lobes folded and fastened together at the edges to form a body with a neck portion, and a bib secured to the body and freely extending from the neck, said bib flaring outwardly from 90 the top to the bottom and ending in laterally extending waist bands which may be drawn about the waist of said body to provide a smooth vest and a girdle.

90

3. An outer garment comprising a body 105 having no waist line and a neck opening cut therein and a bib piece secured to the body and freely depending from the neck opening, said bib flaring outwardly from top to bottom and ending in waist bands 110 which may be drawn about the waist of said body to provide a smooth vest and a girdle.

4. An outer garment comprising a single piece of material formed of a shoulder portion having a neck opening cut therein and front and back lobes folded and fastened together at the edges to form a waistless body with a neck opening, and a bib secured to the body and freely extending from the neck opening, said bib flaring outwardly from top to bottom and ending in waist bands which may be drawn about the waist of said body to provide a smooth vest and a girdle.

15

5. An outer garment comprising a body having no waist line and a neck opening cut therein and a bib piece secured to the body, said bib piece flaring outwardly from top to bottom and ending in waist bands which may be drawn about the waist of said body to provide a smooth vest and a girdle.

20

In witness that I claim the foregoing I have hereunto subscribed my name this 20th day of March, 1920.

MARGARET B. CRANK.
